AUTOMATIC CONTROL MECHANISM

Giles Philip Elliot Howard, Luton, England, assignor to Messrs. George Kent Limited, London, England

Application January 13, 1933, Serial No. 651,608

8 Claims. (Cl. 236—46)

This invention relates to improvements in automatic control mechanism for maintaining a condition such for example as temperature or pressure at any desired steady or varying value.

5 The main object of the present invention is to provide an arrangement which shall be simple to construct, and shall consist of a minimum of parts with consequent reduction in frictional losses and thus requiring small operating force.

10 The invention is illustrated in the accompanying drawing in which Figure 1 is a diagrammatic elevation partly in section, Figure 2 a detail view, and Figure 3 is a fragmentary vertical sectional view on the line 3--3 of Figure 1 with some parts shown in elevation. The particular apparatus 15 shown is arranged to effect control of a gas fed furnace through an opposed fluid pressure nozzle as is claimed in the specification of United States Letters Patent of J. L. Hodgson et al., No. 1,953,406, issued May 5, 1934, but it will be understood that 20 the invention is capable of application to control generally.

1 is a furnace which is heated by a burner 2 fed with gas through a pipe 3 having a control valve 4 therein. 5 is a thermostatic device which is responsive to the value of the temperature of the furnace and is placed in connection through a capillary tube 6 with a device 7 which, in response to temperature change, produces a movement of an arm 8. This arm is connected by a link 9 to an arm 10 having a recording pen 11 thereon, the pen moving over a chart 12 supported by a carrier 12a driven at a predetermined constant speed by a clockwork motor 13 through gearing 14. This arm 10 is mounted to rock about a pivot 15 on which is also mounted a second arm 16 which is connected by a link 17 to a setting device comprising an arm 18 and rotatable member 19 having a groove 20 to receive an operating key which is conveniently the key for winding the motor 13. The arrangement may be such that it is necessary to unlock the casing (indicated at 19') to gain access to the rotatable member.

45 The arms 10, 16 are provided with pairs of pins 21, 22, and 23, 24: which are arranged to receive an arm 25 which is formed at one end with an aperture to receive one of the pins 23, 24 and at the other end is formed with a slot 26 to receive one of the pins 21, 22. In one position the arm 25 is placed in operative relationship with the pins 24, 21 and in an alternative position with the pins 23, 22. This arm 25 is also provided with a pin 27 forming a pivotal mounting for one end of a link

28 whose other end is connected to a chopper blade 29 which is pivotally mounted at 30 and is arranged to be moved more or less into the path of a fluid stream passing from a nozzle 31 to a nozzle 32 which latter is placed in communication through a pipe 33 with a diaphragm 34 having a rod 35 coupled to the valve 4. The arrangement is such that when the arm 10 is coincident with the arm 16 the pin 27 lies over the pivot 15 and thus simultaneous movement of the two arms 10, 16 would not cause any relative movement of the arm 25. If however the arm 10 moves with respect to the arm 16 (as would occur when the temperature varied from the desired value as indicated by the arm 10) the arm 25 is caused by reason of the pin and slot connection 21, 26 to rock about its connection with the arm 16 and this movement is transmitted to the link 28 and thence to the chopper blade 29 which in turn varies the effective fluid pressure transmitted to the diaphragm 34 which finally produces movement of the fuel control valve 4. This control will continue until the value of temperature is restored to the desired value.

It will be observed that a minimum of parts are provided and also that the arm 10 is enabled to move with respect to the arm 16 without restraint. It will also be observed that when the arm 25 engages the pins 21, 24, the arm 25 has a substantial movement towards a position in line with the link 28 as the arm 16 is moved towards the upper limit of the temperature control (i. e. as the arm is rocked in a clockwise direction) and thus for a given angular separation between the two arms 10, 16 the arm 16 transmits a smaller movement to the link 28 when the arm 16 is set nearer the upper limit than when the arm 16 is set nearer the lower limit and thus the sensitivity of control is a maximum at the lower limit and a minimum at the upper limit. The pins 22, 23 however provide an alternative in which the sensitivity is more or less constant over the whole control range, this being effected for the reason that in a mid position of the arm 16 the arm 25 is at or substantially at right angles to the link when the arms 10, 16 are coincident.

In order to provide for a varying extent of movement of the chopper blade 29 for a given movement of the link 28 a plurality of apertures 36 is provided which are spaced at different distances from the pivot of the blade and in order that the blade may be moved either to obstruct or to clear the fluid stream with change in temperature the arrangement may be such as to en- 55

able the relation of the blade arm 28 with respect to the arm 37 thereof to be varied.

In cases where it is desired that the temperature value shall vary with time, the arm 16 may be subject to control exercised by a cam 38 mounted on a hub 18 which is rotated by the motor 13 the cam being shaped to provide any desired variation of value by causing movement of the arm. To effect this control, an arm 16' co-extensive with and secured to the arm 16 is provided below the carrier 12 and engages the cam 38, the weight of the arms being sufficient to maintain the lower arm against the periphery of the cam.

If desired a lost motion arrangement may be provided between the measuring arrangement, e. g. between the arm 8 and the arm 16 so that the arm 16 is not moved until the arm 8 has reached a position corresponding to a predetermined value.

It will be seen that an arrangement according to the invention possesses the following features which are essential in an efficient control apparatus:

(a) There is provided a pointer or indicator which shows at all times the value at which the controller is set to maintain the condition, e. g. the value of temperature.

(b) The setting pointer is unaffected by the movements of the measuring mechanism so that the setting pointer indicates the set value whether the true or actual value coincides with the set value or not.

(c) The setting pointer moves over the same scale as the indicating pointer or recording pen so that when the true value is that at which the controller is set the indication afforded by the setting pointer and the indicating pointer or pen coincides.

(d) The setting pointer has intrinsically the same scale calibration as the indicating pointer or pen.

(e) The set value of the quantity can be varied according to any required time cycle and this is effected by the clock or other means employed to rotate the record chart.

(f) The control mechanism is enabled to be made more sensitive at small values of the variable than at large values and thus uniform accuracy of control may be obtained. It may here be pointed out that a given variation of temperature or other variation from the desired value when this is set at the lower limit of the apparatus will require a larger operation of the controls to cause the conditions to return to the desired value than will the same value of deviation of the condition at the upper limit of the apparatus, the deviation at the upper limit being a smaller fraction of the value of condition than the same deviation at the lower limit. In addition, this variable sensitivity enables the invention to be applied for use with mechanism following a square root relation between control motion and flow; for example, in this type of mechanism, for the first 1/10th of the full flow the measuring device will move 1/100th of the full flow travel, while for half the full flow the measuring device will move quarter of the full travel, and so on.

(g) Provision is made to enable the control mechanism to be set from outside the casing containing the mechanism.

(h) It is possible to provide a suppressed zero to the scale or record, that is to say, the lowest value shown on the scale or chart has some other

value than the true zero of atmospheric pressure temperature or the like.

What I claim is:—

1. In automatic control mechanism, the combination of a setting arm for setting the mechanism to the value at which it is desired to maintain the condition to be controlled, a second arm which is mounted to rock about an axis concentric with that of the setting arm and is displaced in dependence on the value of the condition to be controlled, a third arm pivotally connected to the setting arm and placed in connection with the second arm through a pin and slot connection a control means, a link connecting the control means to the third arm, the point of connection of the link to the third arm being co-axial with the pivotal axis of the setting and second arms when these latter are in a predetermined relative position whereby similar movement of the setting and second arms produces no relative movement of the third arm while departure of these arms from the predetermined relative position effects movement of the third arm and hence of the control device in dependence on the extent of departure.

2. In automatic control mechanism, the combination of a setting arm for setting the mechanism to the value at which it is desired to maintain the condition to be controlled, a second arm which is mounted to rock about an axis concentric with that of the setting arm and is displaced in dependence on the value of the condition to be controlled, a third arm pivotally connected to the setting arm and placed in connection with the second arm through a pin and slot connection, a control means, a link connecting the control means to the third arm, the point of connection of the link to the third arm being co-axial with the pivotal axis of the setting and second arms when these latter are in a predetermined relative position whereby similar movement of the setting and second arms produces no relative movement of the third arm while departure of these arms from the predetermined relative position effects movement of the third arm and hence of the control device in dependence on the extent of departure, the relative position of the third arm and the link being so determined by the points of connection of the arm to the setting and second arms that as the value desired moves towards the upper limit of the mechanism the third arm has a substantial movement towards a position in line with the link so that for a given movement of the third arm in response to separation between the setting and second arms the movement transmitted to the link decreases to reduce the sensitivity of the mechanism.

3. In automatic control mechanism, the combination of a setting arm, a second arm which is displaced in dependence on the value of the condition to be controlled, means operatively connected to and inter-relating the two arms in such manner that the second arm can move without restraint by the setting arm, the inter-relating means being adapted to be actuated by the second arm to an extent dependent on the relative positions of the two arms, and control means which are actuated by the inter-relating means to effect automatic control of the condition to be controlled, the inter-relating means being such as to transmit a smaller movement to the control means as the desired value of control approaches the upper limit of the mechanism.

4. In automatic control mechanism, the combination of a setting arm for setting the mechanism to the value at which it is desired to maintain the condition to be controlled, means for causing the setting arm to assume different positions during a control period, a second arm which is mounted to rock about an axis concentric with that of the setting arm and is displaced in dependence on the value of the condition to be controlled, a third arm pivotally connected to the setting arm and placed in connection with the second arm through a pin and slot connection, a control means, a link connecting the control means to the third arm, the point of connection of the link to the third arm being co-axial with the pivotal axis of the setting and second arms when these latter are in a predetermined relative position whereby similar movement of the setting and second arms produces no relative movement of the third arm while departure of these arms from the predetermined relative position effects movement of the third arm and hence of the control device in dependence on the extent of departure.
5. In automatic control mechanism, the combination of a setting arm for setting the mechanism to the value at which it is desired to maintain the condition to be controlled, means for causing the setting arm to assume different positions during a control period, a second arm which is mounted to rock about an axis concentric with that of the setting arm and is displaced in dependence on the value of the condition to be controlled, a chart carrier, the setting and second arms being adapted to indicate their respective values by reference to a chart on the carrier, a third arm pivotally connected to the setting arm and placed in connection with the second arm through a pin and slot connection, a control means, a link connecting the control means to the third arm, the point of connection of the link to the third arm being co-axial with the pivotal axis of the setting and second arms when these latter are in a predetermined relative position whereby similar movement of the setting and second arms produces no relative movement of the third arm while departure of these arms from the predetermined relative position effects move-
ment of the third arm and hence of the control device in dependence on the extent of departure.
6. In automatic control mechanism, the combination of a setting arm, a second arm which is displaced in dependence on the value of the condition to be controlled, means inter-relating the two arms in such manner that the second arm can move without restraint by the setting arm and such as to be actuated by the second arm to an extent dependent on the relative positions of the two arms, and control means which are actuated by the inter-relating means to effect automatic control of the condition to be controlled, the inter-relating means being capable of alternative connection with the setting and second arms and being in one position arranged to transmit a smaller movement to the control means as the desired value of control moves towards the upper limit of the mechanism and in the second position to transmit a substantially constant movement to the control means over the whole range of control.
7. Mechanism as claimed in claim 2 and in which an alternative position of the third arm relatively to the setting and second arms is provided, in which alternative position a substantially constant movement is imparted to the link in response to separation between the setting and second arms over the whole control range of the mechanism.
8. In automatic control apparatus for controlling a variable condition, the combination of means for setting the apparatus within upper and lower limits to maintain a predetermined value of the condition, means responsive to changes in the condition, control means, and means so inter-relating the setting, the responsive, and the control means that, while the control means is caused to operate throughout the range of the apparatus to an extent dependent on the departure of the condition from the desired predetermined value, a given extent of operation of the control means is produced by a deviation which increases from a minimum at the lower limit of the apparatus to a maximum at the upper limit of the apparatus.

GILES PHILIP ELIOT HOWARD.
